UNITED STATES PATENT OFFICE.

ADOLPH JOHNSON, OF MONTCLAIR, NEW JERSEY.

TENNIS-COURT CORNER-MARKER.

1,037,147.

Specification of Letters Patent. Patented Aug. 27, 1912.

Application filed December 29, 1911. Serial No. 668,524.

To all whom it may concern:

Be it known that I, ADOLPH JOHNSON, a citizen of the United States of America, and a resident of Montclair, in the county of Essex and State of New Jersey, have invented certain new and useful Improvements in Tennis-Court Corner-Markers, of which the following is a specification.

Tennis-courts are customarily marked in a prescribed pattern with a deposit of lime in straight lines or bands of uniform width and meeting at right angles. A common width for these lines is two inches. When the lines are first run a somewhat elaborate measurement and survey is required. As the lines become effaced in course of time, it is necessary to re-mark them at intervals, and, as after stress of weather or at the beginning of a season the lines are more or less completely obliterated, it is particularly desirable that the locations of the points of meeting of the lines should be more permanently marked.

The object of this invention is to provide a suitable stake for such corner marking, whereby remeasurement and resurvey may be avoided.

In the accompanying sheet of drawings, which forms a part of this application, Figure 1 is a perspective of a tennis-court corner-marker constructed in accordance with my invention. Fig. 2 shows a portion of a tennis-court with the marker at the meeting point of two of the court lines.

The marker as shown consists of a cast iron stake having a flat square head *a* and a shank consisting of intersecting webs *b*. The edges of the webs are serrated to increase their hold in the earth. The length of a side of the head is the same as the

width of the lines so that the edges of the head may be used as guides for the locations of the sides of the limed lines. The head may be enameled white to harmonize with the lines and render the marker more easy 45 to find.

The marker is driven into the ground at the junction points of the lines, so that the head will be flush with the surface. An eye *c* is provided at one corner of the head for 50 the connection thereto in any convenient manner, as through a nail *d* inserted in the eye, of a cord *e* which is stretched from one corner marker to another to serve as a guide for one side of the line when applying the 55 lime. The axis of the eye is in line with the adjacent sides of the head. The eye is preferably depressed below the top face of the head so that the nail may be left in the marker without the nail head projecting 60 above the ground.

The usual tennis-court lay out has fourteen corners and junction points at which the markers are to be located.

What I claim as new, and desire to secure 65 by Letters Patent of the United States, is:

1. A tennis-court corner-marker consisting of a stake provided with a flat rectangular head and an eye at one corner of the head. 70

2. A tennis-court corner-marker consisting of a stake provided with a flat rectangular head and an eye depressed below the top face at one corner of the head.

Signed by me at Montclair, N. J. this 75
28th day of December, 1911.

ADOLPH JOHNSON.
